UNITED STATES PATENT OFFICE.

EUGÈNE HENRI LE MOULT, OF PARIS, FRANCE.

ARTICLE DECORATED BY MEANS OF THE WINGS OF INSECTS.

No Drawing. Application filed October 14, 1927, Serial No. 226,262, and in Belgium October 26, 1926.

This invention relates to articles decorated by means of the wings of insects—such as butterflies and the like—either entirely or as to a portion or portions of the said articles.

5 It has already been proposed in the production of pictures to provide a sketch, drawing, print, photograph, silhouette, outline figure or the like having segments or parts of butterflies' wings affixed to the whole or to parts of 10 the said figure or the like for the purpose of representing the same in the natural colours or markings of the wings, parts of the figure, if required, being tinted with a pigment.

According to the present invention the 15 foundation material or article to be decorated is entirely covered, or is covered as to the portion thereof to be decorated with wings or insects, such as butterflies' wings and the surface thus formed is painted, in any 20 suitable manner in order to produce appropriate designs, and to produce appropriate effects in conjunction with the colouring of the wings.

In some cases, wings which have been cut 25 by means of a punch or the like are utilized in the process.

In one method of carrying out the invention a sheet of paper is provided for the foundation and the part to be decorated is entirely 30 covered with the wings of butterflies.

The wings are fixed in position by any appropriate means, as for instance by means of a rapidly drying adhesive, such as one obtained by dissolving gutta percha in benzine 35 or gumlac in alcohol.

In this way a groundwork of butterflies' wings is obtained.

After this a painted design is produced 40 upon the groundwork formed by the wings, so as to constitute a determined picture, pattern or the like.

The design may be produced by means of water colours or oil colours or in some other manner, for instance by the use of wings of birds, tissue paper, leaves made from foil, 45 scales of fishes, natural flowers or leaves or the like.

The picture or design is obtained at relatively low cost and has a very beautiful effect, and it is not necessary to apply a covering 50 glass to the said picture, either plain or with a design produced thereon, or a mask for masking a greater or less portion of the surface.

The invention may be applied for the production of mural pictures or for other purposes, for instance for obtaining decorative panels, for furniture (tables, wardrobes, etc.) or for motor cars, flying machines, hydro-planes or the like; for table articles, office 60 requisites, articles of jewelry, goldsmiths' wares, articles of fashion (dresses, hair ornaments, etc.); and for glass articles (lustres, etc.), the foundation material then being constituted by the articles themselves to be decorated. 65

In some instances the designs may be produced by crayons, coloured powders or the like.

What I claim is:—

The method of decorating articles by means of insects' wings comprising the steps of applying cut out portions of an insect wing to a support by means of an adhesive material, and in then painting a decorative design on the wing material as a ground. 75

In testimony whereof I have hereunto set my hand.

EUGÈNE HENRI LE MOULT.
